[57] CLAIM

The ornamental design for an inhalator, as shown and described.

DESCRIPTION

FIG. 1 is an end elevational view of an inhalator, showing my new design;

FIG. 2 is a top plan view thereof;

FIG. 3 is a bottom plan view thereof;

FIG. 4 is an end elevational view thereof, opposite that shown in FIG. 1;

FIG. 5 is a side elevational view thereof, the opposite side elevational view thereof being a mirror image;

FIG. 6 is a top plan view thereof, with the mouthpiece cover removed;

FIG. 7 is a side elevational view thereof with the mouthpiece cover removed;

FIG. 8 is a top plan view of the mouth piece cover; and,

FIG. 9 is an end elevational view thereof with the mouthpiece cover removed.

FIG. 1

FIG. 2

FIG. 3

FIG. 4

FIG. 5

FIG. 6

FIG. 7

FIG. 8

FIG. 9
